(57) **CLAIM**

The ornamental design for an electric connector, as shown and described.

DESCRIPTION

FIG. 1 is a front elevational view of an electrical connector; FIG. 2 is a rear elevational view thereof;

FIG. 3 is a right side elevational view thereof;

FIG. 4 is a cross-sectional view thereof along the line 4—4 of FIG. 1;

FIG. 5 is a cross-sectional view thereof along the line 5—5 of FIG. 1;

FIG. 6 is a top plan view thereof;

FIG. 7 is a bottom plan view thereof;

FIG. 8 is a perspective view of the front and right side thereof; and,

FIG. 9 is a perspective view illustrating a state in use thereof wherein the electric connector is coupled with a flexible printed cable. In FIG. 9, the broken line shows a flexible printed circuit which is included only to illustrate the environmental structure and forms no part of the claimed design.

A left side elevational view of the electrical connector is omitted because it is presented symmetrical to the right side elevational view of FIG. 3.
